UNITED STATES PATENT OFFICE.

ALVIN C. McCORD, OF CHICAGO, ILLINOIS.

DRAFT-RIGGING.

SPECIFICATION forming part of Letters Patent No. 782,919, dated February 21, 1905.

Application filed February 10, 1902. Serial No. 93,403.

To all whom it may concern:

Be it known that I, ALVIN C. McCORD, a citizen of the United States, residing at Chicago, in the county of Cook and State of Illinois, have 5 invented a certain new and useful Improvement in Draft-Rigging, (Case No. 9,) of which the following is a full, clear, concise, and exact description, reference being had to the accompanying drawings, forming a part of this specification.

My present invention relates particularly to draft-rigging for railway-cars, and has for its object to improve the same in the several particulars hereinafter noted.

15 The invention consists of the novel devices and combinations of devices hereinafter described, and defined in the claims.

In the construction of draft-rigging for cars it has hitherto been customary to connect the 20 draft-bar of the coupler to the car-body through the intervention of one or more springs directly interposed between the draft-bar and some relatively stationary member on the car-body. In practice it has been found 25 that the maximum movement from normal position which can be advantageously allowed to the draft-bar is approximately two inches. Hence a spring or springs applied in this manner must be strong enough to directly 30 resist the intense draft and bumping strains under a compression of two inches or less, or, in other words, under a compression not in excess of the draft-bar movement. As is evident, a spring or springs of such strength will 35 have but very little elasticity under comparatively light strains and will afford an effective cushion only to comparatively heavy strains or impacts. Furthermore, even under heavy blows or impacts a perfectly cushioning action 40 is not afforded, because of the considerable force required to impart an initial movement to the spring or springs.

The principal object of my present invention is to provide an improved construction where- 45 by the coupler may be yieldingly mounted upon the car in such manner that the capacity of the spring or other yielding means em- ployed will be increased and adapted to exert a much greater draw-bar pull or yielding

strain resistance to a bumping strain than has 50 previously been possible with a spring of a given size or strength. This object I accom- plish in a simple manner by the mechanism illustrated in the drawings, wherein a multi- 55 plying lever is interposed between the draft- bar of the coupling and the cushioning-spring in such manner that the spring will be given a compressing movement which is materially greater than the movement of the draft-bar, thus increasing the effective cushioning power 60 of the spring and permitting the use of a lighter spring than could be used under the old arrangements, wherein the force was applied directly to the spring.

The invention is illustrated in the accompa- 65 nying drawings, wherein like characters indicate like parts throughout the several views.

Figure 1 is a side view of draft-rigging con- 70 structed in accordance with my invention, por- tions of the car-body being broken away more clearly to reveal features of the construction. Fig. 2 is a top view thereof. Fig. 3 is a sec- 75 tional view, on the line 3 3 of Fig. 2, of the lever and the associated mechanism. Fig. 4 is a partial sectional view on line 4 4 of Fig. 1. Fig. 5 is a sectional view on line 5 5 of Fig. 1, 80 showing the association of the levers and the draw-bar yoke. Fig. 6 is a sectional view on line 6 6 of Fig. 1. Figs. 7, 8, and 9 are side and end views of the dampener-sleeve which I prefer to employ.

My improved draft-rigging comprises in the preferred embodiment thereof a coupler 1, which is preferably fixedly secured to a coupler-block 2 by means of bolts 3 passing 85 therethrough. The coupler-block transfers the pull of the coupler to the car through the interposition of levers 4, which are fulcrumed upon angle-bars 5 5, which are fixedly secured to draft-timbers 6 6. The draft-timbers 6 6 are rigid with respect to the car-sills 7 7, upon 90 which the car-floor 8 is placed. A cross-bar 9 at the end of the car preferably unites the two side car-sills and at the same time provides a support for the end wall 10 of the car, upon 95 which the buffing-block 11 may be suitably mounted, as is well understood in the art. The cross-bar 9 is suitably recessed, a groove 12

being provided therein, so that the bolts 3 when the coupler is moved forwardly may not engage the said cross-bar. The levers 4 are associated with the coupler-block 2 through 5 the interposition of a draw-bar pin 13 and also with a yoke-block 14 for purposes to be hereinafter set forth. The yoke-block 14 is provided with a yoke-block pin 15, which engages slots 16, provided in the levers 4, which slots 10 are of such size as to permit of a movement of the yoke-bar pin therein longitudinally of the levers. The levers 4 are thus pivotally mounted upon a stationary support associated with the angle-bars 5 and also pivotally 15 mounted upon the yoke-block 14, which is yieldingly secured to the car-framework in the improved manner which I will now describe.

The yoke-block 14 is adapted to transfer 20 the pull of the levers 4 to the car-sills 7 through the interposition of suitable springs 17 and 18, which springs are mounted in a spring-sleeve 19. (Shown most clearly in Figs. 7, 8, and 9.) I prefer to employ a spring-dam- 25 pener, which spring-damper consists of levers 20, suitably arranged to have their flanges pressed outwardly into engagement with the sides of the spring-sleeve 19 when the springs 18 and 19 are compressed, whereby 30 the friction exerted by the levers 20 against the sides of the spring-sleeve 19 exerts a dampening influence upon the action of the springs. The dampeners 20 impinge against a follower 21, while the opposite ends of the springs en- 35 gage a follower 22, both of which followers are mounted in grooves 23, which permit a movement of said followers tending to compress said springs, but which prevent a movement of the followers in a manner to permit 40 an extension of said springs, so that the springs may be confined within certain limits, beyond which they are not permitted to extend, but from which limit they may be compressed any given amount as desired. The 45 grooves 23 are provided in draw-bar stops 24 24, fixedly secured to the car-sills 7.

The yoke-block 14, which transfers the pull of the levers to the car-springs through the interposition of the springs 17 and 18, is connected with the said springs by a draw-bar yoke 25, which is secured to the yoke-block 14 by means of the bolts 26. The draw-bar yoke 25 passes through the spring-sleeve 19 and around the follower 22, so that the levers 50 4 normally exert a pull against the said fol- lower 22. A movement of the levers 4 out- wardly, caused by a pull against the car-cou- 55 pler 1 serves to compress the springs 17 and 18 by the pressure of the draw-bar yoke 25 60 against the said follower. The springs 17 and 18 upon compression serve to press the levers 20 of the spring-damper outwardly against the dampener-sleeve 19, whereby the sudden 65 action of the spring is prevented and a gradu- al pull exerted against the car-sills 7.

The dampener-sleeve 19 which I prefer to employ is shown more clearly in Figs. 6, 7, 8, and 9 and comprises, as shown therein, a circular body portion 27, provided with square ribs 28 28, which ribs are preferably so de- 70 signed as to be capable of engaging the slots 23 and of sliding therein, whereby a rotation of the said sleeve is prevented. The sleeve is also provided with rearwardly-extending projec- 75 tions 29 and forwardly-extending projections 30, which act as checks to prevent too great a movement of the springs. Thus when the follower 22 is moved by a pull exerted through the yoke 25 the said follower presses against the forwardly-extending projections 30 and 80 moves the spring-sleeve 19 longitudinally according to the movement of the said follower. When the spring presses the follower in a backwardly direction, the follower engages a looped extension 31 of the spring-sleeve, 85 whereby it serves to pull the said spring-sleeve back into its original position.

The advantages which my improved con- 90 struction affords are obvious, and the same may be employed not only in connection with draft-rigging for cars, but may also be applied to a number of other uses.

I have found in practice that with the con- 95 struction of my invention as I have proportioned the same for use in railway service with a standard spring of nineteen thousand pounds capacity I am able to exert a draw-bar pull of from forty thousand to sixty thousand pounds, or, in other words, the spring ca- 100 pacity is many times increased, which in- crease depends of course upon the propor- tions employed for the levers 4. The springs may be increased in length to suit the length of the levers, it being preferable to maintain the distance which the draw-bar travels the 105 same as in the recognized standard construc- tions hitherto employed. The dampeners which I prefer to employ in association with the springs control the action thereof and their friction increases the capacity of the 110 springs, as will be readily apparent.

I have herein shown my improved construc- 115 tion as applied particularly with the spring- dampeners shown and claimed in my prior patent, No. 709,998, of date September 30, 1902; but I may use other spring-dampeners, if desired.

It will be apparent that the coupler which I have shown in conjunction with my invention is susceptible of a variety of modifications 120 and any suitable means may be employed for transferring the pull exerted against a cou- pling appliance to the levers, and I do not, therefore, wish to limit myself to the use of any specific device of this character.

I have used the word "coupler" in the claims to signify, broadly, mechanism for transferring the extraneous pull to the levers 4.

From what has been said it will be under- 125 stood that the mechanism above described is

capable of many modifications within the scope of my invention, as herein set forth and claimed.

What I claim, and desire to secure by Letters Patent of the United States, is as follows:

1. In apparatus of the class specified, the combination with a coupler, of lever mechanism connected therewith and a spring-damper mechanism connected with said lever mechanism, said damper mechanism comprising a yoke-block connected with the lever mechanism, a draw-bar yoke secured to said yoke-block, a sliding sleeve connected with said draw-bar yoke, spring means confined in said sliding sleeve and arranged to be acted upon by said draw-bar yoke, levers arranged within said sleeve and consisting of longitudinally-extending portions lying alongside of the longitudinal walls of said sleeve and radially-disposed portions extending transversely of said longitudinally-extending portions, the radially-disposed portions being located opposite the end of said spring means, and an abutment against which the radially-disposed portions of said levers act, said abutment being carried by the car-body, substantially as described.
2. In apparatus of the class specified, a sliding sleeve 19 comprising a portion 27, laterally-extending projections 28, 28, a longitudinally-projecting portion 30, and an end portion 31, substantially as described.
3. In apparatus of the class specified, the combination with the body, of guides 24, 24,

thereon, said guides having guideways 23, 23, 35 and a sliding sleeve 19 comprising a portion 27 provided with lateral projections 28, 28, adapted to fit and work in the guideways 23, 23, substantially as described.

4. In apparatus of the class specified, the combination with the coupler, of spring means tending to resist the movement of the coupler, friction members actuated by said spring means, when subject to tension, to dampen the action thereof, and lever mechanism interposed between the coupler and the spring means, substantially as described.

5. In apparatus of the class specified, the combination with the coupler 1, of levers 4, 4, pivotally connected with the coupler, said connections being between the ends of the pivoted levers, a yoke-block 14 having a sliding connection with the levers near the free ends thereof, a yoke 25 secured to the block 14, springs 17 and 18 confined within the yoke 25, 55 followers 21 and 22 at the ends of the springs 17 and 18, a sliding sleeve 19 inclosing the yoke 25 and actuated by the follower 22, the levers 20, 20, having their longitudinal portions within the sleeve 19 and their transverse 60 portions arranged at one end of the springs 17 and 18, substantially as described.

In witness whereof I hereunto subscribe my name this 29th day of January, A. D. 1902.

ALVIN C. McCORD.
